DESIGN FOR A HANDLE BAR

Samuel A. Snell, Toledo, Ohio, assignor to The American-National Company, Toledo, Ohio, a corporation of Ohio

Application February 7, 1938, Serial No. 74,952

Term of patent 14 years

To all whom it may concern:

Be it known that I, Samuel A. Snell, a subject of the King of Great Britain and Northern Ireland, residing at Toledo, in the county of Lucas and State of Ohio, have invented a new, original, and ornamental Design for a Handle Bar, of which the following is a specification, reference being had therein to the accompanying drawing, forming a part thereof, wherein:

I claim:

The ornamental design for a handle bar substantially as shown.

SAMUEL A. SNELL.
